UNITED STATES PATENT OFFICE.

MARSDEN C. HUTTO, OF DETROIT, MICHIGAN.

GRINDER.

Application filed July 20, 1925. Serial No. 44,644.

This invention relates to grinders and the object of the invention is to provide a grinder for grinding small cylindrical apertures.

Another object of the invention is to provide a grinder in which the operative grinding diameter of the grinding stones may be adjusted to grind exactly to a desired size.

Another object of the invention is to provide a holder of die cast metal in which the grinding stones are embedded, a series of three holders being provided in each grinder adapted to be moved outwardly or inwardly in relation to the grinder body for grinding different diameters.

Another object of the invention is to provide a grinder in which the grinding diameter may be adjusted during the grinding operation.

These objects and the several novel features of the invention are hereinafter more fully described and claimed and the preferred form of construction by which these objects are attained is shown in the accompanying drawings in which—

Fig. 1 is a longitudinal section through a grinder embodying my invention.

Fig. 2 is an elevation thereof.

Fig. 3 is a section taken on line 3—3 of Fig. 1.

Fig. 4 is a section through a smaller grinder of this type.

Fig. 5 is a perspective view of the stone and holder for the smaller grinder.

As shown in Figs. 1, 2 and 3 the grinder consists of a tubular body 1 having a keyway 2 therein in which the key 3 is positioned. A cone 4 is positioned within the tubular body 1 and is provided with a keyway fitting the key 3. The body 1 is provided with a series of three slots opening therethrough and a stone holder 5 is mounted in each slot. A cone 6 is mounted in the end of the tubular body 1 opposite the cone 4 and the stone holders 5 at each end are provided with angular faces fitting the cones 4 and 6.

The body member 1 is provided with an annular groove at each end of the stone holders 5 and the stone holders 5 are each provided with grooves registering with the grooves in the body member 1. A pair of spring rings 7 are positioned in the grooves of the body member and stone holders and by means of the spring rings 7 the stone holders are held in engagement with the cones 4 and 6. The cone 6 is rotatably mounted on a shaft 8 which is threaded into the cone 4 and the end of the

shaft 8 extending through the cone 6 is secured in an adjusting knob 9 by the pin 10. The knob 9 is provided with a knurled face 11 and by turning the knob 9 in one direction in relation to the body 1, the shaft 8 secured thereto is threaded into the cone 4 thus drawing the cones 6 and 4 together. In this operation both cones are moved equally and move the three holders 5 outwardly against the tension of the spring rings 7. In the form shown in Fig. 1 each holder 5 is provided with two stones 12. The holders 5 are formed of die cast metal and are cast with the angular faces fitting the cones 4 and 6 and with the grooves for the spring rings 7. The stones 12 are die cast in the holders 5 and the stones 12 are held in the mold while the holder is being die cast so that the stones 12 are in perfect alignment and are each parallel with the longitudinal axis of the respective holder. In this way the stones 12 are always true in the holders and this type in which two stones are utilized is adapted for grinding two apertures to the same size at the same time such as the two wrist pin holes in a piston. The grinder is driven by means of the shaft 13 which is connected to the body 1 by a universal connector 14. The grinder is inserted in the wrist pin apertures of a piston with the stones 12 engaging the walls of the apertures. As the grinder body is rotated the grinding stones grind the inside walls of the apertures until the stones begin to free themselves at which time the operator may grasp the knob 11 for an instant while the tool is rotating which turns the shaft 8 in relation to the grinder body 1 to move the cones 4 and 6 together slightly. This increases the grinding diameter of the stones slightly and this operation may be repeated until the apertures are ground to size.

To reset the tool to a smaller diameter the knob 11 may be rotated to unscrew the shaft 8 in the cone 4 and the spring rings 7 contract the stone holders 5 and force the cones apart as the shaft 8 is unthreaded in the cone 4 and by this arrangement the cones 6 and 4 are moved apart equally until the desired smaller diameter is reached.

A slightly different form of tool is shown in Figs. 4 and 5 in which a tubular body member 15 is provided having a shank 16 adapted to be secured in a chuck by which the tool is rotated. With this form the cone 17 is notched to fit the key 18 which fits in a

keyway in the body member 15 and the shaft 19 is threaded into the cone 17. The cone 20 is formed integrally with the knurled knob 21 and is secured to the shaft 19 5 by the pin 22. The holders 23 are die cast with the grinding stones 24 embedded therein and are provided with angular faces 25 fitting the cones 17 and 20. There are three holders 23 provided which extend 10 through the body member in the same manner as the holders shown in Fig. 3. The body member is provided with two annular grooves for the spring rings 26 and the holders are provided with grooves 27 for the said spring 15 rings. This device is utilized for grinding apertures of small diameter and is adjusted in the same manner as the form shown in Figs. 1, 2 and 3. By turning the knob 21 the shaft 19 is threaded into the cone 17 to move the 20 cones 17 and 20 together and move the holders and stones outwardly radially from the center of the tool and by reversing the rotation of the knob 21 the cones 17 and 20 are moved apart and the holders 23 are retracted radially by the spring rings 26 which hold the 25 holders 23 in engagement with the cones.

From the foregoing description it becomes evident that the device is very simple and efficient in operation, will not easily get out of 30 order, may be utilized for accurately grinding small cylindrical apertures, and provides a tool in which the stone holders may be easily replaced.

Having thus fully described my invention, 35 its utility and mode of operation, what I claim

and desire to secure by Letters Patent of the United States is—

1. In a grinder for truing cylindrical apertures, a hollow body member, a series of abrasive holders mounted in the body member and 40 adapted for movement radially therein, a pair of cones in the body member, a shaft extending between the cones and adapted by rotation to vary the distance apart of the cones, said holders being formed with integral tapered 45 portions at opposite ends to fit the respective cones and spaced abrasive members carried at opposite ends of the holders, the cones and connecting shaft being movable as a unit on longitudinal axis of the body and limited in 50 such movement by reason of engagement with the respective tapered portions of the stone holders, the cones positively fixing the general limit of contraction of the abrasive devices in 55 operation.

2. In a grinder for truing cylindrical apertures, a hollow body member having a series of longitudinally extending radial slots therein, a series of abrasive holders fitting the said slots, means in the body for adjusting the 60 holders radially in the slots, and an abrasive member adjacent each end of each holder providing a tool with a series of abrasive elements in longitudinally spaced relation adapting the 65 same for grinding pairs of spaced apertures in axial alignment.

In testimony whereof I sign this specification.

MARSDEN C. HUTTO.
